CABLE GRIP

Filed Dec. 14, 1931

FIG. 1

FIG. 2

Inventor
William J. Buehring
By *Jacob & Baumer* Atts

UNITED STATES PATENT OFFICE

WILLIAM J. BUEHRING, OF CHICAGO, ILLINOIS

CABLE GRIP

Application filed December 14, 1931. Serial No. 580,753.

My invention relates to cable grips of the split sleeve type such for example as are shown in the United States patent to Whaley No. 1,769,479.

It is the principal purpose of this invention to provide a grip of this character with a novel means whereby the same may be utilized for pulling heavy cables without the work of hooking the sides together becoming burdensome because of the great number of hooks necessary.

In a device such as shown in the patent, the loops along the sides of the split sleeve are laced together by means of a series of single hooks or clips fastened to one side and hooking into the other side. So long as a few wires and not too strong a grip is required so that about a dozen hooks is all that need be used, that is quite satisfactory. However, when this cable grip is adapted to work requiring a stronger grip and a much greater strength, a considerably greater number of wires must be used and this rapidly increases the number of loops which must be hooked together. Furthermore, the wires are closer together in the stronger grips which does not make them any easier to hook.

This invention contemplates the provision of a novel hooking device whereby the number of hooking operations necessary to connect together the two sides of the split sleeve is reduced to less than one-half the total number of loops on either side of the split sleeve.

I will describe the preferred form of my invention by reference to the accompanying drawings wherein—

Fig. 1 is a side view of a grip as applied to a cable;

Fig. 2 is a perspective view of the hook employed showing how it is engaged with a loop by a simple tool.

Referring now in detail to the drawings, the numeral 3 refers to a cable of common form. The grip 4 is made up, as in the prior patent mentioned, of a plurality of strands

of wire such as 5, 6, 7, and 8 which strands are inclined with respect to the axis of the body so that they pass helically from the one edge 9 to the other edge 10 and back. At one end the strands are attached together in pairs as indicated at 11 while at the other end they are united to form the hand grips 12 and 13.

In order to connect the opposite loops along the two side edges 9 and 10 of the split sleeve, I provide the members 14 which, as shown most clearly by Fig. 2, consist of metal plates having along the one side edge 15 a plurality of hooked projections 16, 17, and 18 while on the opposite side a single hook 19 is provided, this single hook 19 being somewhat heavier than the hooks 16, 17, and 18. In practice, the small hooks 16, 17, and 18 are permanently attached to the loops as indicated in Fig. 1, and the plates 14 are alternately attached to opposite sides of the split sleeve in the fashion shown in Fig. 1.

It is believed to be clear from the above description and the illustration that in lacing up the sleeve it is necessary to make only one hook 19 hook into its corresponding loop 20 for each three loops when counted lengthwise of the sleeve.

However, when the ends of the sleeve are approached, it is necessary to provide a special type of hook so that the two end loops such for example as 21 and 22 in Fig. 1 will be fastened together. This special type of connecting hook is shown at 23 and includes the two permanent fastenings 24 and 25 similar to 16 with the hook member 26 similar to 19. As shown, two of these types of hooks are used, and in addition a single hook 27 similar to that shown in the patent is employed at the hand grip end of the sleeve. This hook 27 may be dispensed with if desired.

From the above description, it is believed to be clear that the novel means of hooking the split sleeve together effects a considerable saving in the amount of time and work neces-

sary to fasten or to unfasten the sides of the sleeve.

Having thus described the invention, what is claimed as new and desired to be secured by Letters Patent is:

6. 1. In a cable grip having a body portion consisting of a split sleeve composed of strands so interlaced as to form a series of loops at each longitudinal edge thereof, hook members for securing the opposite edges of said sleeve together, said hook members being connected to more loops on one side edge than on the other.
10. 2. In a cable grip having a body portion consisting of a split sleeve composed of strands so interlaced as to form a series of loops at each longitudinal edge thereof, hook members for securing the opposite edges of said sleeve together, said hook members being connected to a plurality of said loops on one side edge and having a loop receiving member for engaging a loop on the other side edge of said sleeve.
15. 3. In a cable grip having a body portion consisting of a split sleeve composed of strands so interlaced as to form a series of loops at each longitudinal edge thereof, hook members for securing the opposite edges of said sleeve together, said hook members being connected to a plurality of said loops on one side edge and having a loop receiving member for engaging a loop on the other side edge of said sleeve, alternate hook members being attached to opposite side edges of said sleeve.
20. 4. In a cable grip having a body portion consisting of a split sleeve composed of strands so interlaced as to form a series of loops at each longitudinal edge thereof, hook members for securing the opposite edges of said sleeve together, said members each comprising a connecting plate having a plurality of loops of one side edge of said sleeve slidably hooked thereto at spaced points along the edge thereof and having a hook for engaging a single loop on the other side edge of said sleeve.
25. 5. In a cable grip having a body portion consisting of a split sleeve composed of strands so interlaced as to form a series of loops at each longitudinal edge thereof, hook members for securing the opposite edges of said sleeve together, said members each comprising a connecting plate having a plurality of loops of one side edge of said sleeve slidably hooked thereto at spaced points along the edge thereof and having a hook for engaging a single loop on the other side edge of said sleeve, each of said plates being connected opposite to the adjacent plates whereby all of said loops are connected to plates.
30. 6. In a cable grip having a body portion consisting of a split sleeve composed of strands so interlaced as to form a series of loops at each longitudinal edge thereof, hook

members for securing the opposite edges of said sleeve together, said members each comprising a connecting plate having three loops of one side edge of said sleeve slidably hooked thereto at spaced points along the edge thereof and having a hook for engaging a single loop on the other side edge of said sleeve.

In witness whereof, I hereunto subscribe my name this 4th day of December, A. D. 1931.

WILLIAM J. BUEHRING.
